UNITED STATES PATENT OFFICE.

MERWIN GASKILL, OF GRAND RAPIDS, MICHIGAN.

DESIGN FOR A COMBINED BILLIARD AND POOL SIGN.

60,525.

Specification for Design.

Patented Mar. 7, 1922.

Application filed March 18, 1921. Serial No. 453,404. Term of patent 14 years.

To all whom it may concern:

Be it known that I, MERWIN GASKILL, a citizen of the United States, residing at Grand Rapids, in the county of Kent and State of Michigan, have invented a new, original, and ornamental Design for Combined Billiard and Pool Signs, of which the following is a specification, reference being had to the accompanying drawing, forming a part thereof.

In the drawing, Fig. 1 is a side elevation of the sign; Fig. 2 is an edge elevation of a design of the same showing light bulbs upon both sides of the rack.

a represents the rack, and *b* represents the several light bulbs, the latter being designed to be colored as the several billiard or pool balls are colored, and illuminated electrically, especially at night and upon very dark days, or in dark rooms and hallways.

I claim:

The ornamental design for a combined billiard and pool sign, as shown.

Signed at Grand Rapids, Michigan, March 12, 1921.

MERWIN GASKILL.
